UNITED STATES PATENT OFFICE.

ARTUR MOLLENKOPF, OF LUBECK, GERMANY.

WINDOW, ESPECIALLY FOR RAILROAD, TRAMWAY, AND OTHER VEHICLES.

Application filed July 6, 1920. Serial No. 394,399.

To all whom it may concern:

Be it known that I, ARTUR MOLLENKOPF, citizen of Germany, residing at 73 Konigstrasse, Lubeck, Germany, have invented 5 certain new and useful Improvement in Windows, Especially for Railroad, Tramway, and Other Vehicles, of which the following is a specification, reference being had thereto in the accompanying drawing.

10 This invention relates to windows for vehicles, and it has for its objects, among others, to provide a novel construction whereby the window can be easily turned into the various desired positions and rendered 15 versed for cleaning or other purposes.

Other objects and advantages of the invention will hereinafter appear and the novel features thereof will be particularly pointed out in the appended claims.

20 The invention is clearly illustrated in the accompanying drawing, which, with the numerals of reference marked thereon, form a part of this specification, and in which— Figure 1 is an elevation with portions 25 broken away and parts in section.

Figure 2 is a vertical section.

Figure 3 is a detail partly in horizontal section.

Figure 4 is a vertical section showing the 30 window in one position.

Figure 5 is a similar view showing the window in a different position.

Figure 6 is a similar view showing the window in still a different position.

35 Figure 7 is a sectional detail with the parts in still a different position.

Like numerals of reference indicate like parts through the different views.

In the drawings:

40 1 designates a window frame in which are affixed the boxes 4. Each box is provided, within the same, with a curve 6 having a stop member 7. A two-armed member 8—9 has one end or the other co-operate 45 with this curve and stop, as shown clearly in Figures 2 and 7. This member or lever 8—9 is carried by the pin 11 carried by the sash 10, as seen clearly in Figure 1. This pin works in the rectangular opening 5 in 50 the box 4, as seen clearly in Figures 1, 2, 4, 5, 6 and 7. The turning point when the sash is swung out is changeable, describing, as it were, a quadrangular outline, as will be readily understood from the various views.

55 12 is a spring affixed at one end within a corner of the box, as seen in Figures 2 and

4 to 7, with its free portion bearing against the pin 11, and assists in the movements of the sash and to keep the same tight in its closed position.

At the upper and lower edge of the frame are ledges. As seen in Figure 2, the bottom member 2 has the grooved ledge 15, while the upper member 3 of the frame has a catching ledge 16 on the outside, and the 65 projections 13 and 14 cooperate therewith, as seen in Figure 2. The lower edge has a lifting handle 17, and the upper edge has a similar handle 18.

The operation is as follows:

Supposing the parts to be in the position seen in Figure 2, the sash is lifted by the handle 17 until the member 13 is moved out of the groove 15 and the arm of the lever is brought out of the curve away from the 70 stop 7. The upper sash slides upward on the ledge 16 and the pin 11 lies against the upper edge of the cut out 5, as seen in Figure 4. Now the lower edge is pulled outward from the frame so that the member 80 14 stands against the ledge 16, and the pin 11, against the influence of the spring 12, is pulled over the cut out to the opposite side. Then a pull of the sash downward will bring the upper edge out of its engagement 85 with the frame and the pin 11 takes its lowermost position in the cut out 5, as seen in Figure 6, and the lowermost arm of the lever corner comes in contact with the inclination 19 at the bottom of the box, as seen 90 in Figure 6, and the sash is out of the plane of the members 2 and 3 and is free for turning movement on the pin 11.

If the handle 17 is pulled to the front, the spring 12 at the same time pushes on the pin 95 11 so that the arm 8 comes against the front of the offset or stop 7 and thus the turning movement is started. Now, by lifting the handle 17, the upper part of the sash swings downward so that the arm 9 rides on the 100 curve 6, as seen in Figure 7. The arm 9 slides downward on this curve and lifts the sash so far as to permit the member 14 riding on the incline 20 and jumping into the groove 15. The pressure of the spring 12 105 prevents all rattling of the sash when closed.

What is claimed as new is:

1. A window structure comprising a frame provided with an upper cross bar and a sill, a sash reversibly mounted in said frame with 110 the rail at the top thereof normally spaced from the horizontal surface of said cross bar

and the rail at the bottom normally engaged with said sill, and means for swingingly associating said sash with said frame, said means comprising a box carried by a jamb of said frame and provided with an opening and a pivot pin carried by the sash and extending into said opening, the distance between the opposite walls of said opening being greater than the diameter of said pin whereby the sash may be raised to clear the sill, then moved laterally and downwardly to clear the lintel, and then swung toward reversed position while the pin rests on the bottom wall of the opening.

15. 2. The structure according to claim 1 wherein there is a cam shaped member in the box adapted to support said pin.

3. The structure in accordance with claim 2 wherein said pin comprises oppositely extending arms adapted to engage the said cam surface as the sash moves toward reversed position to raise said sash, whereby the rails at the top and bottom thereof may be brought into normal relation with said cross bar and sill respectively.

4. A frame, a box thereon with a rectangular opening, a sash in said frame, a pin

carried by the sash extended into the box through said opening and laterally movable in the latter and engageable with the walls of said opening, a two-armed member carried by said pin, and a cam surface in said box with which the end of either one of said arms is adapted to engage, said pin and member reversibly supporting the sash.

5. A frame, a box thereon with a rectangular opening, a sash in said frame, a pin carried by the sash extended into the box through said opening and laterally movable in the latter and engageable with the walls of said opening, a two-armed member carried by said pin, a cam surface in said box with which the end of either one of said arms is adapted to engage, said pin and member reversibly supporting the sash and a stop member at one end of said cam to limit the movement of the engaging arm along said cam surface.

In testimony whereof I affix my signature in the presence of two witnesses:

ARTUR MOLLENKOPF.
